(57) **CLAIM**

The ornamental design for a bottle tote, as shown and described.

DESCRIPTION

FIG. 1 is a perspective view of a bottle tote, shown in use with bottles;

FIG. 2 is a front view of the bottle tote;

FIG. 3 is a back view thereof;

FIG. 4 is a side view thereof;

FIG. 5 is a top view thereof;

FIG. 6 is a bottom view thereof; and,

FIG. 7 is a perspective view of the bottle tote, shown in a cinched configuration with different bottles.

The dot-dot-dash broken lines depict bottles that are not part of the claimed design, and the dot-dot-dot broken lines represent stitching that is claimed.

1 Claim, 7 Drawing Sheets---
